(57) **CLAIM**

The ornamental design for a building as shown and described.

DESCRIPTION

FIG. 1 is a front, left and upper perspective view of a first embodiment of a building showing my new design, the first embodiment having an opaque top.

FIG. 2 is a front perspective view thereof;

FIG. 3 is a rear perspective view thereof;

FIG. 4 is a right side perspective view thereof;

FIG. 5 is a left side perspective view thereof; and

FIG. 6 is a top view thereof.

FIG. 7 is a front, left and upper perspective view of a second embodiment of a building showing my new design, the second embodiment having a transparent top.

FIG. 8 is a front perspective view thereof;

FIG. 9 is a rear perspective view thereof;

FIG. 10 is a right side perspective view thereof;

FIG. 11 is a left side perspective view thereof; and,

FIG. 12 is a top view thereof.

1 Claim, 12 Drawing Sheets
